203,311

HYDROTHERAPY BATH UNIT

Samuel L. McNair, Fullerton, Calif., assignor to The Songrand Corporation, a corporation of Missouri

Filed Mar. 31, 1965, Ser. No. 84,525

Term of patent 14 years

(Cl. D83—1)

Fig. 1.

Fig. 2.

Fig. 3.

Fig. 4.

Fig. 5.

Fig. 6.

FIG. 1 is a side elevational view of the hydrotherapy bath unit embodying my design; the other side is substantially the same as this side;

FIG. 2 is a top plan view of same;

FIG. 3 is a sectional view taken along the line 3—3 of FIG. 2 in the direction of the arrows;

FIG. 4 is a bottom plan view of the device;

FIG. 5 is an end view of same taken from the right hand end of FIG. 1; and

FIG. 6 is an end view of same taken from the left hand end of same.

I claim:

The ornamental design for a hydrotherapy bath unit, as shown and described.
